UNITED STATES PATENT OFFICE.

GEORGE A. TUCKFIELD, OF SALT LAKE CITY, UTAH.

STOVE OR RANGE.

SPECIFICATION forming part of Letters Patent No. 707,989, dated August 26, 1902.

Application filed January 13, 1902. Serial No. 89,487. (No model.)

To all whom it may concern:

Be it known that I, GEORGE A. TUCKFIELD, a citizen of the United States, and a resident of Salt Lake City, in the county of Salt Lake 5 and State of Utah, have invented a new and Improved Stove or Range, of which the following is a full, clear, and exact description.

This invention relates to improvements in stoves or ranges; and the object is to provide a simple device for increasing or diminishing the fire-space and grate area, so that more or less fire may be maintained as occasion may require, resulting in an economy of fuel when a small fire is desired.

15 I will describe a stove or range embodying my invention and then point out the novel features in the appended claims.

Reference is to be had to the accompanying drawings, forming a part of this specification, 20 in which similar characters of reference indicate corresponding parts in both the figures.

Figure 1 is a perspective view, partly in section, of a stove or range embodying my invention; and Fig. 2 is a plan view thereof.

25 Referring to the drawings, 1 designates a stove or range, 2 the fire-box, and 3 the grate therein. A partition - plate 4 is movable lengthwise of the grate, and this partition-plate has hinge connection 5 with a leaf 6, 30 which in turn has hinge connection with a leaf 7, hinged, as at 8, to the fire-brick or to a side of the stove. The partition 4 stands at all times vertical, and as a means for moving it back and forth I employ an operating-rod 35 consisting of a section 9, passing through an opening in one end of the range and engaging with the partition 4. This rod 9 connects with a rod-section 10, which, as here shown, passes along the outer side of the stove 40 and is movable in guides 11. In some instances, however, it may move inside the stove and have a handle portion extended through the wall, so that it may be readily grasped. In Fig. 1 and in dotted lines in 45 Fig. 2 the partition 4 is shown at its extreme position in reducing the grate area.

When a larger grate area and fire-space is desired, the rod 10 is to be moved, and consequently the partition 4 will be drawn back, the hinges 5 permitting the plate 6 to move 50 upward, and the plate 7 will also move upward. The extreme rearward position of the partition and plates is shown in Fig. 2 in full lines.

It is obvious that the partition may be 55 brought forward when the fire is in full blast, and thus all the fire may be brought under one hole of the stove, and the shape of the partition may be made to conform to any desired range. 60

Having thus described my invention, I claim as new and desire to secure by Letters Patent—

1. In a stove or range, a partition extended vertically from the grate and movable thereon, a plate extending across the grate and having hinge connection with the partition, another plate having hinge connection with the first-named plate and hinge connection with the stove or range, and a rod for operating the partition, substantially as specified. 65

2. In a stove or range, a partition extended upward from the grate and movable along the same, a plate extended across the grate and having hinge connection with the lower end 75 of the partition, another plate having hinge connection with the first-named plate and also having hinge connection with the stove or range, a rod having a portion extended from the partition through an opening in the 80 stove, and a portion extended along the outer side of the stove, substantially as specified.

In testimony whereof I have signed my name to this specification in the presence of two subscribing witnesses.

GEORGE A. TUCKFIELD.
